(57) **CLAIM**

The ornamental design for a rotary saw cut alignment guide, as described and shown.

DESCRIPTION

FIG. 1 is a perspective view of the rotary saw cut alignment guide of the invention;

FIG. 2 is a top view of the rotary saw cut alignment guide of FIG. 1;

FIG. 3 is a bottom view of the rotary saw cut alignment guide of FIG. 1;

FIG. 4 is a front view of the rotary saw cut alignment guide of FIG. 1, the rear view being identical;

FIG. 5 is a left side elevational view of the rotary saw cut alignment guide of FIG. 1; and,

FIG. 6 is a right side elevational view of the rotary saw cut alignment guide of FIG. 1.
